Primary Examiner — S. Bryan Reinholdt, Jr.*Assistant Examiner* — James T Tyree(74) *Attorney, Agent, or Firm* — Ashley D. Johnson; Dogwood Patent and Trademark Law(57) **CLAIM**

The ornamental design for a self-adjusting shade, as shown and described.

DESCRIPTION

FIG. 1 is a front perspective view of a new design for a self-adjusting shade with the canopy in an extended position via the wind;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The evenly spaced broken lines depict portions of the self-adjusting shade that form no part of the claimed design. The self-adjusting shade includes a symbolic break along its length drawn in dot-dash-dot broken lines. The broken break lines and the area in between the break lines form no part of the claimed design.
